US00D538424S

(12) **United States Design Patent** (10) **Patent No.:** **US D538,424 S**
Zahn et al. (45) **Date of Patent:** **** Mar. 13, 2007**

(54) **DISPENSING CONTAINER**

(75) Inventors: **Walter Zahn**, Columbia, SC (US);
Shawn W. Miller, Columbia, SC (US);
David Rocheleau, Lexington, SC (US);
Mohammad R. Sadeghi, Columbia, SC (US);
Bernd Hansen, Laufen (DE)

(73) Assignee: **Holopack International Corp.**,
Columbia, SC (US)

(**) Term: **14 Years**

(21) Appl. No.: **29/218,010**

(22) Filed: **Nov. 24, 2004**

(51) **LOC (8) Cl.** **24-02**

(52) **U.S. Cl.** **D24/115**
